UNITED STATES PATENT OFFICE.

IRVING C. JENNINGS, OF SOUTH NORWALK, CONNECTICUT.

CENTRIFUGAL PUMPING APPARATUS.

Application filed March 18, 1926. Serial No. 95,737.

This invention relates to a centrifugal pumping apparatus, particularly of the motor-driven type.

In the commercial manufacture of such pumping apparatus, the provision of suitable supporting bearings and driving connections for the motor and the pump impeller has been found to involve considerable difficulty. The pump and the motor are commonly manufactured as separate units, often in different plants, and when assembled they frequently present substantial variations in height and alignment.

It has been considered very desirable to mount the pump directly upon a rigid extension of the motor shaft, avoiding the expense and complication of separate and additional bearings in the pump casing. This combination has been found unsatisfactory, however, on account of the necessity for very close and accurate alignment of the motor and the pump casing.

It is an important object of my present invention to provide a construction by which a centrifugal pump and motor may be conveniently assembled and by which the necessity for extremely accurate alignment may be avoided.

To the attainment of this object, I mount the impeller directly upon an extension of the motor shaft and I provide a stuffing box on the pump casing which may be slightly adjusted radially to provide for slight variations in alignment between the motor bearings and the pump casing.

I also provide a floating or self-centering sealing device in the pump casing for the wall opening in the impeller chamber into which the impeller shaft extends.

By the combination of these two devices, I provide a construction which may be easily and cheaply assembled without the necessity for extremely accurate alignment of the parts. This construction has been found very effective and reliable in operation.

As a feature of this construction, I preferably provide a centrifugal pump in which the impeller has a substantial radial clearance in all parts of its chamber and in which the packing of the stuffing box is sufficiently yielding so that it will adapt itself to slight

variations in the angular relation of the impeller shaft thereto.

A further object of my invention is to provide an air pump for priming purposes, rotatable in its own separate bearings on the pump casing, but driven by a self-aligning connection from the impeller shaft which is supported by the main bearings of the driving motor.

My invention further relates to arrangements and combinations of parts which will be hereinafter described and more particularly pointed out in the appended claims.

A preferred form of the invention and several modifications are shown in the drawings in which

Fig. 1 is a front elevation, partly in section, of a motor driven centrifugal pump of the double suction type and adapted to work under a positive head;

Fig. 1^a is a detail section of the extreme upper part of the pump casing;

Fig. 1^b is a detail sectional view showing the driving connection between the motor and pump;

Fig. 1^c is a detail section, taken along the line c—c in Fig. 1^b;

Fig. 2 is a sectional front elevation of a double suction centrifugal pump, designed for operation under a negative head and provided with a separate priming pump supported upon its own individual bearings and driven by the impeller shaft through a self-aligning connection;

Fig. 3 is a sectional front elevation of a double suction centrifugal pump, having a separate priming pump mounted directly upon an extension of the impeller shaft;

Fig. 4 is a sectional front elevation of a single suction centrifugal pump, having a separate priming pump mounted on individual bearings;

Fig. 5 is a view similar to Fig. 3 but showing a single suction pump;

Fig. 6 is a view similar to Fig. 1 but showing a single suction pump;

Fig. 6^a is a detail section of the extreme portion of the pump casing;

Figs. 7, 8 and 9 are sectional front elevations of the different parts forming the casing of a double suction centrifugal pump;

Fig. 10 is a front elevation of the impeller for the same pump; and

Figs. 11, 12 and 13 are enlarged sectional details of certain of the parts shown in Fig. 2.

- 5 Referring particularly to Fig. 1, I have shown a motor driven centrifugal pump of the double suction type. I have provided a solid and substantial base 20 upon which a motor M may be secured by bolts 21 or in 10 any other convenient manner. While the motor may be of any suitable construction or method of operation, I have indicated an electric motor having an armature or rotor 22 mounted on a driving shaft suitably supported in bearings 23 fixed in the motor frame 24. Only one bearing 23 is shown in Fig. 1 but it will be understood that a second bearing will be provided at the left hand 15 end of the motor, as indicated at Fig. 6. 20 Preferably one or both of the bearings 23 will be in the form of a thrust bearing adapted to limit end play of the motor shaft 25 in both directions.

25 The centrifugal pump P shown in my drawings comprises a casing preferably formed in two parts which may be conveniently referred to as the volute or main casing member 26 and the cover member 27. An impeller chamber 28 is preferably formed integral with the volute casing member 26 and a water space 29 is provided between the left hand wall of the impeller chamber 28 and the left hand wall 30 of the pump casing. The cover member 27 is also provided with 30 an inner wall 31 spaced from the outer cover and forming the right hand side of the impeller chamber. The space between the cover 27 and the inner wall 31 forms an additional water space 32 through which water may be 35 delivered to the right hand side of the impeller 33, which rotates freely and with substantial clearance within the impeller chamber 28.

40 A pet cock 29^a (Fig. 1^a) is provided to permit removal of air from the water spaces. The impeller 33 may be of a construction common in such pumps and its hub 33^a is mounted upon an impeller shaft 34 which in effect forms an extension of the motor shaft 25. The impeller shaft 34 may be secured to the motor shaft in any convenient manner but I prefer to use the construction indicated in Figs. 1^b and 1^c, in which a cylindrical recess 35 is formed in the end of the impeller shaft 34, to receive the outer end of the motor shaft 25.

45 The shaft 25 is freely slideable axially in the recess 35 but is provided with a key 36 which prevents relative angular movement of the pump shaft and the impeller shaft. A screw 37 is provided to hold the parts in the desired axial relation after assembly.

50 The impeller shaft 34 extends through an opening 40 (Fig. 1) in the left hand side wall of the pump casing and is provided

55 with a stuffing box 41 having a soft annular packing 42 secured therein by a gland or retaining member 44. Any suitable means (not shown) may be provided for forcing the gland inward to compress the packing. A 70 so-called lantern packing 45 may be inserted in the stuffing box as indicated in Fig. 1 and may be connected to a water supply pipe 46 to provide a water seal for the stuffing box 41. 75

The stuffing box 41 is secured to the side wall 30 of the pump casing by bolts 47 passing through radial slots in the flange 48 of the stuffing box. The inward extension 49 of the stuffing box is slightly smaller in diameter than the opening 40, so that the stuffing box may be slightly adjusted radially and may be secured in any desired radial adjustment by the bolts 47.

80 This slight radial adjustment is of very great importance in my present invention as will be hereinafter more fully explained.

85 The impeller hub 33^a extends through an axial opening 50 in the left hand side wall of the impeller chamber 28 and I have made 90 special arrangements for sealing the space between the periphery of the impeller hub and the inside of the opening 50. For this purpose, I provide a self-adjusting or self-centering sealing device comprising a ring 52 closely fitting a cylindrical surface on the impeller hub and a second ring 53 fitting a recess or dépression 54 in the side wall of the impeller chamber. The rings 52 and 53 are 95 freely slideable radially relatively to each other within a limited range and are pressed 100 yielding against each other by springs 55 mounted on studs 56 having their heads seated in the rings 52, said studs extending through slots in the openings or rings 53. In 105 a double suction pump as shown in Fig. 1, a similar sealing device is also preferably provided at the right hand side of the impeller.

110 By the construction above described, the manufacture and assembly of a motor driven centrifugal pump is very greatly simplified. The motor is assembled with the base 20 and is secured thereon by the bolts 21. The pump casing is then placed on the base 20 and is moved axially to cause the shaft 25 to enter the recess 35, the stuffing box 41 being loosely secured to the pump casing during assembly.

115 When the parts are in the desired relation, the screw 37 will be inserted to fix the axial relation, and the stuffing box 41 may then be secured in radially adjusted position on the pump casing by the bolts 47. If for any reason the motor shaft 25 should not be in exact alignment with the stuffing box 41, the soft packing 42 will adapt itself to such slight angular divergence between the shaft and the stuffing box. In the meantime, the self-centering sealing devices formed by the rings 52 and 53 will have adapted themselves to the position assumed by the motor shaft 25 and impeller shaft 34, leaving the impeller 120 125 130

free to rotate about its own center, while at the same time it is sealed in the impeller chamber and leakage of water therefrom is prevented. The shelf-centering sealing devices will also adapt themselves to such very slight angular divergence as may occur between the axis of the motor shaft and the axis of the impeller chamber.

While somewhat similar sealing devices and stuffing boxes may have been previously and separately employed for special purposes, I derive very important mechanical and commercial advantages by combining in one structure a radially adjustable stuffing box for the impeller shaft and a self-centering sealing device for the impeller, as by this construction I am able to assemble separately-manufactured pump and motor units, without requiring unreasonable accuracy in 15 the height or alignment of the motor shaft and the pump casing.

In Fig. 2, I have shown a double centrifugal pump similar in its general construction to that shown in Fig. 1, but showing 20 also the provision of an air pump for priming purposes. It is well known that a centrifugal pump of the impeller type depends for its action upon the outward or centrifugal movement of water in the impeller passages. 25 If the water is all removed from the passages and the pump is operating under a negative head, it is necessary to prime the pump before it will again start into operation, as it has no lifting properties until 30 water is supplied for the impeller passages. For such priming purposes, I have provided an air pump 60 mounted on the outer wall 61 of the pump casing and connected to withdraw air from the water space 62 surrounding the impeller chamber 63, thus causing 35 water to flow into the water space 62 and fill the impeller passages, starting the pump in operation.

I have indicated the pump 60 as being of 40 the hydroturbine type shown in the prior patent to Nash, No. 1,091,529 issued Mar. 31, 1914, and comprising a rotor 64 mounted on a shaft 65 supported in bearings 66 and 67 carried by a rigid frame extension 68 secured to the pump casing member 61.

The frame member 68 is preferably provided with an annular storage space 69 in which a supply of make-up water for the air pump 64 may be retained, the priming water flowing to the pump through suitable 55 passages 70. This make-up water replaces any of the operating water of the air pump which may be discharged from the pump in the form of vapor or which may be otherwise lost.

A driving member 71 forms a self-aligning connection between the impeller shaft 72 and the rotor shaft 65. The end of the impeller shaft is preferably threaded externally to receive a threaded nut 73 and has

a recess 74 to receive one end of the driving member 71. The member 71 is prevented from rotating in the recess 74 by a cross pin 75 fitting slots 76 in the side walls of the recess 74. The nut is held from rotation 70 by a cross pin 77 and also acts as a binding nut for the impeller hub retaining it securely on its shaft.

At its opposite end, the driving member 71 is provided with a cross plate 78 loosely 75 fitting a corresponding slotted recess in the body of the rotor 64 and transmitting rotary movement thereto.

A sealing member 80 fits closely on the external surface of the shaft 72 and is pressed against a finished surface 81 on the inside of the pump casing wall, the sealing device being self-centering and the action being similar to that of the sealing rings previously described.

The air pump thus constructed is a single self-contained unit which may be quickly and easily removed from the pump when desired and which rotates freely about its own axis, without requiring exact alignment with the 90 axis of the impeller shaft 72 or exact positioning axially relatively thereto.

In Fig. 3, I have shown a double centrifugal pump of the general type indicated in Figs. 1 and 2, but designed for operation under a negative head. I have provided a priming pump 90 mounted on the cover plate 91 of the pump casing, with a rotor 92 supported directly upon an extension 93 of the impeller shaft 94. I have provided a sealing ring 95 for the impeller shaft or hub, substantially as described with reference to Fig. 2. I have also made special provision for accurate axial or longitudinal adjustment of the rotor 92 on the impeller shaft extension 93, such adjustment being rendered necessary in order that the rotor may be axially positioned accurately within the air pump chamber.

For this purpose, I provide screw threads 110 upon the end portion of the shaft extension 93, said threads fitting the inside of a double threaded sleeve 96. The outside of the sleeve is threaded to fit a threaded recess 97 in the body of the rotor 92. The internal and external threads of the sleeve 96 are preferably of the same hand but of different pitches, so that a very fine differential axial adjustment may be obtained by rotating the sleeve. The parts are secured in any desired relation by 120 a cross pin 98.

The details of this axial adjusting mechanism are not claimed herein but form the subject matter of an additional application, Serial No. 101,827, filed April 13, 1926.

The combination of the radially adjustable stuffing box 41, the self-centering sealing members for the impeller hub, and the sealing ring 45 for the extension of the impeller shaft to the air pump permit the rotating parts of the 130

centrifugal pump and of the air pump to align themselves with the motor shaft, and do away with the necessity for extremely close and accurate alignment of these separate units.

In Fig. 4, the construction is substantially similar to that previously described, except that the centrifugal pump is of the single suction type for negative head. The air pump is supported as in Fig. 2 upon its own individual bearings and is flexibly connected with the end of the impeller shaft.

In Fig. 5, the construction is similar in a general way to that shown in Fig. 3, with the exception that the centrifugal pump is of the single suction type and an extra storage space 100 is provided for priming water for the air pump 101.

In Fig. 6, I have shown my improvements as applied to a single suction centrifugal pump designed to operate under a positive head and thus requiring no priming air pump for its operation.

Having thus described my invention as applied to several different combinations of centrifugal pumping apparatus and having fully pointed out the important advantages derived from the combination of elements herein described, it is believed that further and additional description of the operation will not be found necessary.

Furthermore, I do not wish to be limited to the details herein disclosed otherwise than as set forth in the claims, but what I claim is:—

1. In a centrifugal pumping apparatus, a base, a driving member rotatably mounted in fixed bearings on said base, a centrifugal pump having a casing fixed relative to said driving member bearings and forming an impeller chamber, an impeller supporting member forming a rigid extension of said driving member and extended through an opening in one wall of said chamber to the interior thereof, a stuffing box for said impeller supporting member mounted for slight radial adjustment on said pump casing, and a self-centering sealing device effective to seal the opening in the wall of said impeller chamber around said impeller supporting member.

2. The combination in a centrifugal pumping apparatus as set forth in claim 1, in which the stuffing box is provided with a yielding packing permitting the impeller supporting member to rotate about an axis slightly oblique to the axis of said stuffing box.

3. In a centrifugal pumping apparatus, a base, a driving member rotatably mounted in fixed bearings on said base, a centrifugal pump having a casing fixed to said base and forming an impeller chamber, an impeller for said pump rotatable in said chamber, an impeller supporting member forming a rigid extension of said driving member and ex-

tended through an opening in one wall of said chamber to the interior thereof, a stuffing box for said impeller supporting member mounted for a slight radial adjustment on said pump casing, and a self-centering sealing device effective to seal the opening in the wall of said impeller chamber around said impeller supporting member and to permit said member to find its own center relative to said casing opening.

4. In a centrifugal pumping apparatus, a base, a driving member rotatably mounted in fixed bearings on said base, a centrifugal pump having a casing fixed relative to said driving member bearings and forming an impeller chamber, an impeller for said pump rotatable in said chamber, an impeller supporting member forming a rigid extension of said driving member and extended through an opening in one wall of said chamber to the interior thereof, a stuffing box for said impeller supporting member mounted for slight radial adjustment on said pump casing, and a self-centering sealing device having a portion floating with said impeller supporting member and effective to seal the opening in the wall of said chamber around said impeller supporting member.

5. In a centrifugal pumping apparatus, a base, a motor having a rotating driving shaft, a motor casing fixed to said base and having fixed bearings for said shaft, a centrifugal pump having a casing fixed to said base and having an impeller chamber with an opening in one side wall substantially aligned with said driving shaft, an impeller rotatable in said chamber but having substantial radial clearance at all parts thereof, an impeller supporting member forming with said driving shaft a rigid rotatable member extending into said pump casing and through said wall opening into the impeller chamber, a stuffing box for said rotatable member mounted on said pump casing, securing means for said stuffing box permitting slight radial adjustment thereof on said casing, and a self-centering sealing device effective to seal the wall opening around said impeller supporting member.

6. In a centrifugal pumping apparatus, a motor having a rotating driving shaft, a motor casing having fixed bearings for said shaft, a centrifugal pump having a casing fixed relative to said motor casing and having an impeller chamber with an opening in one side wall substantially aligned with said driving shaft, an impeller rotatable in said chamber and having substantial radial and axial clearance at all parts thereof, an impeller supporting member forming with said driving shaft a rigid rotatable member extending into said pump casing and through said wall opening into the impeller chamber, a stuffing box for said rotatable member mounted on said pump casing, and a sealing

ring surrounding said impeller supporting member at said wall opening and radially self-adjusting relative to a second sealing member supported by said chamber side wall.

5 7. In a centrifugal pumping apparatus, in combination, a centrifugal pump having a casing with an impeller chamber therein, an impeller for said pump mounted in said chamber on a rigid rotatable driving member extending within said chamber, means to support and rotate said driving member in fixed bearings, said supporting and rotating means being external to and separate from said pump and casing and determining the 10 axis of rotation of said impeller, said impeller having substantial radial clearance in said impeller chamber, a stuffing box for said rotating driving member on said pump casing, adjustable radially for alignment with said 15 driving member, means to secure said stuffing box to said pump casing in adjusted position, and a self-centering sealing device effective to prevent leakage from said impeller chamber around said driving member.

20 8. The combination in a centrifugal pumping apparatus as set forth in claim 7, in which said stuffing box has a slightly yielding packing permitting a slight variation in angular alignment of said driving member with said 25 casing and stuffing box.

30 9. The combination in a centrifugal pumping apparatus as set forth in claim 7, in which said stuffing box has a slightly yielding packing permitting a slight variation in angular alignment of said driving member with said 35 casing and stuffing box, and in which said sealing device also permits a similar slight variation in angular alignment of said impeller shaft relative to said impeller casing without attendant leakage.

40 10. In a centrifugal pumping apparatus, in combination, a centrifugal pump having a casing with an impeller chamber therein, an impeller for said pump mounted in said chamber on a rigid rotatable driving member extending within said chamber, means to support and rotate said driving member in fixed bearings, said supporting and rotating means being external to and separate from said pump and casing and determining the 45 axis of rotation of said impeller, a radially adjustable stuffing box for said driving member mounted on said pump casing, a self-centering sealing device for said driving member in said impeller chamber, a priming air pump having a casing mounted in substantial alignment with said impeller chamber, a rotor in said air pump mounted in bearings fixed in said air pump casing, and a 50 self-aligning driving connection between said rotor and the driving member of said centrifugal pump.

55 11. In a centrifugal pumping apparatus, in combination, a centrifugal pump having a casing with an impeller chamber therein, an

impeller for said pump mounted in said chamber on a rigid rotatable driving member extending within said chamber, means to support and rotate said driving member in fixed bearings, said supporting and driving 60 means being external to and separate from said pump and casing and determining the axis of rotation of said impeller, a radially adjustable stuffing box for said driving member mounted on said pump casing, a self-centering sealing device for said driving member in said impeller chamber, a priming air pump having a casing mounted in substantial alignment with said impeller chamber, a rotor in said air pump mounted in bearings fixed in said air pump casing, a driving connection between said rotor and the driving member of said centrifugal pump permitting slight variations in alignment between said rotor and said driving member, and a self-centering sealing device for said driving member between said centrifugal pump and said air pump.

65 12. A centrifugal pumping apparatus comprising a base, a motor having a frame 70 mounted on said base, a centrifugal pump having a casing separately and rigidly mounted on said base, said casing having a separate impeller chamber enclosed thereby and mounted in fixed relation thereto but 75 having side walls substantially spaced therefrom, a motor shaft rotatable in fixed bearings in said motor frame, an impeller rotatable in said impeller chamber but rigidly secured to an extension of said motor shaft and supported by said motor bearings, and sealing means for said shaft in said pump casing and for said shaft extension in one of said impeller chamber walls, said sealing means being adaptable to variations in both 80 the axial and radial position and alignment of said shaft relative to said pump casing and of said extension relative to said impeller chamber.

85 13. The combination in a centrifugal 90 pumping apparatus as set forth in claim 12, in which a priming air pump is provided having a rotor rotatable in bearings fixed relatively to said centrifugal pump casing, and in which a self-aligning driving connection is provided between said rotor and said 95 shaft extension, and in which an additional floating sealing device is provided for the driving connections between said air pump and said centrifugal pump, positioned at the 100 outer wall of the centrifugal pump casing.

105 14. In a centrifugal pumping apparatus, a base, a motor having a rotating driving shaft, a motor casing mounted on said base and having fixed bearings for said shaft, a centrifugal pump having a casing mounted in fixed relation to said motor casing and having an impeller chamber with an opening in one side wall substantially aligned with said 110 driving shaft, an impeller rotatable in said 115

chamber, an impeller supporting member forming with said driving shaft a rigid rotatable member extending into said pump casing and through said wall opening into the impeller chamber, a stuffing box for said rotatable member mounted on said pump casing, securing means for said box permitting

slight radial adjustment thereof on said casing, and a self-centering sealing device effective to seal said wall opening around said impeller supporting member. 10

In testimony whereof I have hereunto affixed my signature.

IRVING C. JENNINGS.
